UNITED STATES PATENT OFFICE.

WILLIAM H. LLOYD, OF EVANSTON, ILLINOIS, ASSIGNOR TO CRANE COMPANY, OF CHICAGO, ILLINOIS, A CORPORATION OF ILLINOIS.

CLOSET-BOWL.

No. 851,679.

Specification of Letters Patent.

Patented April 30, 1907.

Application filed October 29, 1904. Serial No. 230,563.

To all whom it may concern:

Be it known that I, WILLIAM H. LLOYD, a citizen of the United States, residing at Evanston, in the county of Cook and State of Illinois, have invented certain new and useful Improvements in Closet-Bowls, of which the following is a specification.

My invention relates to improvements in closet bowls of the type provided with a rim outlet and has for its object the more perfect cleansing of the bowl.

A further object is the conservation of the force of the water at the point where it is most needed.

These and such other objects as may hereafter appear are attained by the devices shown in the accompanying drawings, in which—

Figure 1 is a perspective view of the preferred form of my invention. Fig. 2 is an enlarged plan view of Fig. 1, with the seat down. Fig. 3 is an enlarged detail, partly in section, on the line 3—3 of Fig. 2, looking in the direction indicated by the arrows; and Fig. 4 is a plan view or a modification of my invention, with a portion broken away.

Like letters of reference indicate the same parts in the several figures of the drawings.

Referring by letter to the accompanying drawings, A represents the bowl of a closet, B the rim preferably formed to provide a seat-supporting shoulder, which at its front is formed with a raised lip C.

D is the seat, cut away at E to receive the lip C.

Referring to Fig. 3: The raised lip or flushing rim C is curved downwardly, terminating in a depending portion or apron F. The deflecting flange G rises under the apron F and forms one wall of a water chamber I. Between the top g of the deflecting flange G and the opposite wall of the apron F is the water discharge opening J, which may be of any convenient character. The water chamber I is preferably continued around the bowl, as shown beneath the rim at I'. With this construction it will be seen that, as soon as the chamber I is substantially filled with water, whenever the usual flushing valve is opened

the hydrostatic pressure will force the water through the outlet J with uniform force at all points. The constriction of the outlet J will, of course, tend to create powerful jets which will be directed by the form of the outlet J against the sides of the bowl.

With the preferred form of my invention, it will be noted that the cleansing jets will be directed against the upper part of the front of the bowl from a level which is higher than the top of the main rim. Hence, the lip C and associated parts not only furnish the front of the bowl with protection against overflow at that point, but afford more effective means for cleansing the bowl at that point.

In the modified construction of Fig. 4, I have shown the bowl with the lip C' extending around the entire circumference of the bowl, in which construction the seat D may, or may not, be cut away to accommodate the lip C' in which event the top of the lip C' will be flush with the seat, while the weight of the seat will be supported mainly or wholly by the shoulder or rim B. The advantages of such construction are obvious.

While I have illustrated two embodiments of my invention, it is evident that, other modifications thereof and variations therefrom may be made, without departing from the spirit of my invention.

I claim:

1. The combination with a closet bowl provided with a seat supporting shoulder and with a flushing rim rising from the inner side of said shoulder, of a seat adapted to be supported by said shoulder and to extend substantially flush with the top of said rim.

2. The combination with a closet bowl provided with a seat supporting shoulder and with a flushing rim rising from the inner side of said shoulder, of a seat arranged to be supported by said shoulder and constructed so as to conform to said rim.

3. The combination with a closet bowl provided with a seat supporting shoulder and with a flushing rim rising from the inner side of said shoulder, of a seat constructed and arranged to be supported by said shoulder and to receive said flushing rim.

4. The combination with a closet bowl provided with a seat supporting shoulder and with an upwardly extending flushing rim, of a seat adapted to be supported by said shoulder and arranged to extend around the outer face of said flushing rim.

5. The combination with a closet bowl, provided with a flushing rim of a seat constructed and arranged to extend around the outer face of said flushing rim and means for supporting the under face of said seat in a plane below the top of said flushing rim.

6. The combination with a closet bowl provided with a flushing rim of a seat arranged to extend around the outer face of said flushing rim, said seat being recessed to receive said rim and means for supporting the under face of said seat in a plane below the top of said flushing rim.

7. The combination with a closet bowl provided with a rim and having a regular, unbroken form in its horizontal dimensions, one portion of which is elevated above the rest and has an elevated flushing outlet on its interior surface, of a seat formed to accommodate such elevated portion, and means constructed and arranged to support said seat with its upper surface substantially

flush with the upper surface of the elevated portion of the rim.

8. The combination with a closet bowl provided with a flushing rim having a regular, unbroken form in its horizontal dimensions, one portion of which is elevated above the rest and has an elevated outlet on its interior surface, of a seat adapted to rest on said rim with its upper surface substantially flush with the upper surface of the elevated portion of the rim, and being cut away to accommodate such elevated portion.

WILLIAM H. LLOYD.
